UNITED STATES PATENT OFFICE.

JOSEPH W. SCHLOSS, OF NEW YORK, N. Y.

DESIGN FOR TRIMMING.

SPECIFICATION forming part of Design No. 21,648, dated June 21, 1892.

Application filed April 23, 1892. Serial No. 430,419. Term of patent 3½ years.

To all whom it may concern:

Be it known that I, JOSEPH W. SCHLOSS, a citizen of the United States, residing in New York, in the county of New York and State of New York, have invented a new and original Design for Trimming, of which the following is a specification.

My design for trimming is fully illustrated in the accompanying drawing, in which the figure illustrates my new and original design.

The design comprises a central flat strip of braid or material similar to braid. This strip, which is lettered *a* in the drawing, occupies the middle portion of the trimming, and cord *b* extends in a zigzag direction across the face and throughout the length of it. This cord crosses the edges of the braid and is formed into small complete loops *b'*. The braid has an edging on each side, consisting of a series of loops *c*, which are arranged concentric with the loops *b'*, the adjacent ends of the loops coming together and forming a scalloped edge. Each complete loop on the edge may be made up of one or more cords, all concentric with each other. In the design shown there are

two of such cords in each loop besides the loop formed by the cord *b*. The trimming is traversed by several bands *d d*, &c., of looped threads.

The essential features of the design are the central braid-like strip having a cord extending in a zigzag direction across its face throughout its length, said cord crossing the edges of the braid and being bent into complete loops, and a row of loops of one or more concentrically-placed cords on each side of the braid-strip, the ends of the loops coming together and forming a scalloped edge. 35

I claim—

The design for a trimming, substantially as herein described, and as shown in the accompanying drawing. 40

In witness whereof I have hereunto signed my name in the presence of two subscribing witnesses.

JOSEPH W. SCHLOSS.
